UNITED STATES PATENT OFFICE.

HENRY C. CAMPBELL, OF TARRYTOWN, NEW YORK, ASSIGNOR TO WILLIAM N. CAMPBELL, OF SAME PLACE.

METHOD OR PROCESS OF MAKING KEGS, BARRELS, &c.

SPECIFICATION forming part of Letters Patent No. 533,435, dated February 5, 1895.

Application filed February 10, 1894. Serial No. 499,703. (No model.)

To all whom it may concern:

Be it known that I, HENRY C. CAMPBELL, a resident of Tarrytown, Westchester county, State of New York, have invented certain new and useful Improvements in Methods or Processes of Making Kegs, Barrels, &c., of which the following is a specification.

My invention relates to the manufacture of kegs, barrels and similar receptacles by steaming and bending wood to form sections of the same, and has for its object to produce a keg, barrel or like packing vessel especially adapted for the storage of paint and similar heavy liquid or semi-liquid materials.

15 To this end my invention consists in the method or process of bending wood herein-after set forth, and more particularly pointed out in the claim.

In processes hitherto in use for the purpose 20 of forming the staves or segments of kegs, barrels or the like, it has been customary to cut gores or kerfs in the stock employed where it is desired to contract the same, thus imparting the desired curvature to them, 25 while in my process I bend whole unkerfed, ungoresed slabs both with and across the grain, at a single operation incidentally imparting to the segment treated two or more distinct curvatures, as will more fully hereinafter appear.

30 In the drawings, forming part hereof—Figure 1 is an orthographic side view of an apparatus for carrying out my improved method or process, which will be more fully described hereinafter. Fig. 2 is a perspective view of 35 two sections comprising the walls of a form of my improved keg or barrel before they are united. Fig. 3 is a side view of a head or cover to co-operate with a closure ring in the 40 end of my improved keg. Fig. 4 is an orthographic side view partly in section of a form of my improved keg, having a closure ring applied to one end thereof. Fig. 5 is a plan view of the head or cover shown in Fig. 3.

45 My improved apparatus shown in Fig. 1 consists of a mold having a male and a female die A and B respectively, each the counterpart of the other, and having a working face or surface of the shape of a section of a keg 50 or barrel. This section may be in extent any portion of the circumference of a keg, but I

prefer to make it a semi-circumference as I have found that two halves of a keg may be very readily joined. These dies may be operated by any suitable devices, such, for instance, as a press, as shown in Fig. 1, the same consisting of a bed-plate *a* upon which one of the dies rests, standards *b b* supporting a cross-head *c* together with a screw *d* carrying the other die or member of the mold 55 passing through the cross-head *c*, and working in a thread tapped therein and having a cross-bar or crank *e* at the free end thereof. The die which rests upon the bed-plate *a* is stationary, and the die carried by the screw *d* is movable, and is moved with relation to the fixed die by means of the screw. Suitable guides *f f* may be formed on the standards *b b* with which may co-operate arms *g g* carried by the moving die and serving to guide 60 the die in its movement.

The dies A and B are preferably made hollow and have suitable pipe systems *h j* for providing a supply of heated fluid to heat the dies, to more rapidly and efficiently dry 75 the wood. As I have before stated, these dies are so shaped as to give to the wood the shape of a section of a keg, that is to say, to impart both a longitudinal and a transverse curvature thereto.

80 In practicing my process I place between the dies, as shown in Fig. 1, a slab of wood D of suitable extent previously steamed to a degree sufficient to render the same highly flexible and reinforce the same on the side 85 which is to form the outside circumference of the keg with a sheet or strip *k* of metal or other suitable material less flexible than wood laid loosely against the face thereof. The dies are now brought together with considerable pressure and the wood is bent into shape, the metallic sheet or strip *k* serving to prevent splitting of the wood as the transverse bend is being imparted thereto, it being remembered in this connection that the 90 grain is in the direction of the longitudinal axis of the keg. This keg section is allowed to remain in the heated mold until dry or set, and is then removed. Two or more of these keg sections may be built up into a keg.

95 The employment of a sheet or strip of metal in bending the keg sections I deem of espe-

cial importance as by its use I am enabled to overcome the liability of the wood splitting, when being bent in the direction of the grain.

In Fig. 2 I have shown two semi-sections E 5 E forming the walls of a keg made by steaming and bending, as described. These sections may be crozed and chamfered, as shown, at $l m$, for the reception of a head n , as shown in Fig. 4. These sections E E may be united 10 at their edges $o p$ in any suitable manner, as by glue, and hoops $q q$ may be put around the keg to more firmly retain the sections in place. The keg may be headed up at both ends in any desired manner, or I may head 15 up one end in the ordinary manner and provide the keg with a special closure at the other end, as shown in Figs. 3, 4 and 5. This closure consists of a metallic ring G fitting into the end of the keg and having a screw-threaded portion r , a shoulder or bead u , a depending, inclined or curved lip s , and a securing flange t overlapping the end of the keg, together with a head or cover H screw-threaded on its edge, and adapted to engage 20 with the screw-threaded portion of the ring G. 25

It will be observed that by my invention I am enabled to construct a substantial vessel such as a keg or the like, from flat slabs of wood without any waste of material and at little cost; little time being employed in uniting the parts and the necessity of skilled labor dispensed with. 30

It will be obvious that my method or process may be variously practiced, so therefore I do not limit myself to the precise mode of 35 procedure described herein, but

What I claim, and desire to secure by Letters Patent, is—

The herein described method of making kegs and the like from whole unkerfed, un-gored flat pieces of wood, which consists in steaming the wood to give the requisite flexibility, reinforcing the same with a sheet or strip of less flexible material, and then pressing the wood thus reinforced in a mold to impart the desired shape thereto, as described. 40 45

HENRY C. CAMPBELL.
